CONVERSION OF COMPOUNDS OF THE
ACETYLENE SERIES

Albert Auerhahn, Neckargemuend, and Robert
Stadler, Heidelberg, Germany, assignors to I.
G. Farbenindustrie Aktiengesellschaft, Frank-
fort-on-the-Main, Germany

No Drawing. Application April 26, 1938, Serial
No. 204,462. In Germany May 11, 1937

3 Claims. (Cl. 260—680)

The present invention relates to a process of converting compounds of the acetylene series into compounds of the ethylene series.

It is already known that compounds of the acetylene series may be converted into compounds of the ethylene series by treating them with an aqueous suspension of zinc dust activated by means of copper sulphate. The utilization of the zinc when working in the said manner is, however, unsatisfactory.

We have now found that compounds of the acetylene series can be converted into compounds of the ethylene series in a considerably more advantageous manner and with very good yields by treating compounds of the acetylene series with aqueous suspensions of zinc dust which has been activated by treating same with aqueous solutions of copper and cadmium salts.

The said zinc dust may be obtained for example by introducing powdered zinc into an aqueous solution of a copper salt and then, after the precipitation of the desired amount of copper, further treating with a solution of a cadmium salt. The solutions of copper and cadmium salts may also be allowed to act on the zinc powder simultaneously. The hydrogenation may also be carried out by means of a suspension of zinc dust in an aqueous solution of a copper and cadmium salt. The presence of the said three metals is essential in all cases, but other metals may be present besides.

The proportions in which the cadmium is admixed to the zinc and copper may vary within a wide range. An amount of $\frac{1}{20}$ molecular proportion of cadmium for one molecular proportion of zinc may be sufficient.

When using zinc dust activated in the said manner, the conversion of the acetylene linkage into the ethylene linkage proceeds at least four times as rapidly as when using zinc dust which has been activated with copper alone. Contrary to expectation, only relatively small amounts of hydrogen are formed in the hydrogenation according to the present process, so that the utilization of the zinc is very favorable. Moreover, the hydrogenation of the acetylene linkage proceeds only to the formation of the ethylene linkage without any appreciable formation of the corresponding saturated compounds. Even when acetylene compounds which contain olefinic double linkages in addition to the triple linkages are hydrogenated, the hydrogenation is limited to the triple linkages. The present invention, therefore, can most advantageously be used for the conversion of vinylacetylene into butadiene.

Inert gases, as for example nitrogen or carbon dioxide, may be present during the hydrogenation. Solvents, especially those having solvent power for acetylene hydrocarbons and not being attacked under reaction conditions, such as the alcohols, may also be added to the suspensions. The co-employment of dispersion agents or stabilizers, as for example Turkey red oil, alkylated naphthalene sulphonate acids, sulphonates of high molecular weight alcohols, addition products of a plurality of molecular proportions of ethylene oxide to high molecular weight alcohols, or the fatty acid amides of taurine, has proved advantageous in order to produce the most intimate possible contact between the reactants. The temperature and the pressure may be varied within wide limits, but the reaction proceeds to good results even at ordinary or slightly elevated temperature, e. g., from 40° to 100° C. and at atmospheric pressure. The process may be carried out in an uninterrupted manner or continuously and also in a cycle. In the latter case it is preferable to separate the constituents of the acetylene compound already hydrogenated before repeated leading into the reaction vessel, for example by washing out, condensation and fractional distillation.

The following examples will further illustrate how the said invention may be carried out in practice, but the invention is not restricted to these examples.

Example 1

20 grams of zinc dust are shaken for a short time with dilute hydrochloric acid and then washed. The still moist zinc dust is shaken with a solution of 20 grams of copper sulphate and 4 grams of cadmium chloride in 200 cubic centimeters of water for from 5 to 10 minutes and washed several times with water. The zinc dust treated in the said manner is shaken for half an hour at 50° C. in a vessel containing 150 cubic centimeters of water and 500 cubic centimeters of acetylene. Within the said time 84 per cent of the acetylene is converted into ethylene. The gas obtained contains only 2 per cent of hydrogen.

When working in the same manner, but with a zinc powder containing copper alone but no cadmium, there are obtained within the same time only 5.8 per cent of ethylene together with 8.5 per cent of hydrogen, while 83.3 per cent of acetylene remain unconverted.

Example 2

- 75 grams of zinc dust are treated for 2 minutes with dilute hydrochloric acid, washed out and shaken with a solution of 75 grams of copper sulphate in 500 cubic centimeters of water. After all the copper has been precipitated, the zinc-copper powder is shaken for about 10 minutes in a solution of 10 grams of cadmium chloride in 200 cubic centimeters of water and then washed thoroughly. The zinc dust thus pretreated is shaken with 500 cubic centimeters of water and 10 liters of gaseous vinyl acetylene in a vessel at a temperature between 40° and 70° C. After an hour, 69.1 per cent of the vinyl acetylene is converted into butadiene. Only 6 per cent of the hydrogen formed are not used for the hydrogenation.
- A zinc dust which has been treated only with copper yields only 12 per cent of butadiene under otherwise identical conditions.

Example 3

- A zinc powder treated as described in Example 2 is shaken with 10 liters of gaseous vinyl acetylene and 500 cubic centimeters of water to which 2 cubic centimeters of Turkey red oil have been added for an hour at from 40° to 70° C. The gas contains 71.2 per cent of butadiene, no hydrogen and no methane hydrocarbons.

Example 4

- 20 grams of zinc powder treated in the manner described in Example 1 with 20 grams of copper sulphate and 4 grams of cadmium chloride are added to 465 grams of phenylacetylene and 300 cubic centimeters of water. The whole is heated at 50° C. for about one hour in a vessel while stirring. Within this time, the phenylacetylene is converted into styrene except small traces thereof.

By working in the same manner, but with a zinc

copper powder containing no cadmium, 52 per cent of the phenylacetylene are not at all converted within the same time.

Example 5

150 grams of zinc dust are treated in the manner described in Example 2 with copper sulphate and cadmium chloride. The zinc dust thus pretreated is admixed with 1500 cubic centimeters of water and 0.2 gram of the sodium salt of oleic acid tauride are filled into a vertical glass tube having a diameter of 80 millimeters. 12 liters of vinylacetylene are bubbled through this mixture in a cycle, thus causing the temperature to exceed 40° C. In the course of 1½ hours 84.2 per cent of the vinylacetylene are thus converted into butadiene. The formation of hydrogen does not exceed 2 per cent of the resulting gases.

What we claim is:

1. A process for the conversion of compounds of the acetylene series into those of the ethylene series which consists in treating compounds of the acetylene series with an aqueous suspension of zinc dusts which has been activated by treating same with aqueous solutions of copper and cadmium salts.

2. A process for the conversion of compounds of the acetylene series into those of the ethylene series which consists in treating compounds of the acetylene series at from 30° to 90° C. with an aqueous suspension of zinc dust which has been activated by treating same with aqueous solutions of copper and cadmium salts.

3. A process for the conversion of vinylacetylene into butadiene which consists in treating vinylacetylene at from 30° to 90° C. with an aqueous suspension of zinc dust which has been activated by treating same with aqueous solutions of copper and cadmium salts.

ALBERT AUERHAHN.
